UNITED STATES PATENT OFFICE.

ORVILLE F. KIME, OF CRESTLINE, OHIO.

DISPLAY-RACK.

1,138,488.

Specification of Letters Patent.

Patented May 4, 1915.

Application filed July 1, 1914. Serial No. 848,370.

To all whom it may concern:

Be it known that I, ORVILLE F. KIME, a citizen of the United States, and a resident of Crestline, in the county of Crawford and 5 State of Ohio, have invented certain new and useful Improvements in Display-Racks, of which the following is a specification.

My invention relates to racks for displaying articles for sale, such as rugs, and the 10 main object thereof is to so support a plurality of said articles as to be readily displayed individually.

A further object is to provide such a rack from which any desired one of the articles 15 on display can be easily removed, without disturbing any of the other articles thereon.

A further object is to provide such a device whereby the weight of the displayed articles serves to lock the same more firmly 20 on the rack.

A further object is to provide such racks which may easily be moved from place to place, which require little floor space, which hold many of the articles on display, and 25 which are comparatively inexpensive.

My invention is fully described in the following specification, of which the accompanying drawings form a part, in which the separate parts are designated by the same 30 reference characters in each of the views, and in which:—

Figure 1 is a perspective view of my invention, ready for use; and Fig. 2 is a side elevation thereof, in use, with articles displayed thereon.

In the drawings forming a part of this application I have shown a rack comprising two end members *a* and *b*, joined by transverse braces *c*, *c*² and *c*³, the first of which 40 has a strip *c*⁴ arranged thereon, segmentally formed, and through which are passed a plurality of pointed barbs *c*⁵.

The end member *a* consists of front and rear uprights *a*² and *a*³, the latter considerably higher than the former, and joined by braces *a*⁴ and *a*⁵, the latter of which is provided with casters *a*⁶, and the member *b* consisting of front and rear uprights *b*² and *b*³ joined by braces *b*⁴ and *b*⁵ and the latter 50 of which is provided with similar casters.

Pivoted to the front uprights *a*² and *b*² is a frame *d* formed of side bars *d*²—*d*², and transverse bars *d*³ and *d*⁴, the former of which has a segmental strip *d*⁵ thereon having barbs *d*⁶ upwardly directed therefrom,

and it will be noted that the pivotal point of the said frame is somewhat nearer the lower ends of the side bars than the upper ends, thus causing said frame to normally incline in the direction of and lean on the 60 transverse brace *c*, approximately as shown in Fig. 1, and said transverse bars are joined by means of slats *d*⁷.

In the present showing rugs *e* are displayed, being arranged on the frame *d* at 65 first, said frame having been moved into the vertical position indicated by dotted lines in Fig. 2, in such manner that the barbs *d*⁶ pass through the rugs at a point nearer the upper end than the lower of said rugs, in 70 the positions shown, whereby a portion of said rugs will depend to the rear of the frame but the major part will depend at the front thereof and, when the frame is moved into its full line position, the weight thereof 75 and of the rugs serves to bind said rugs against the brace *c*, it being assumed that all the rugs are now in front of the frame, ready for individual display.

After the outer rug has been inspected it 80 may be thrown backwardly so that it depends from the brace *c* to the rear of the rack, and all of the rugs may be so inspected and thrown into rearward position, successively, and there is no danger of any 85 of the rugs escaping from the rack because of the barbs *c*⁵ and *d*⁶ but, if it is desired to remove one for sale or for other inspection, all that is necessary is to raise the frame *d* away from the brace *c*, remove the desired 90 rug, and permit the frame to resume normal position, the rugs on either side of the one desired being thrown over either the brace *c* or the frame *d*, or both, this removal of one rug not disturbing the others in the 95 slightest.

My invention is simple, but well adapted to the purpose for which it is designed, and I may make changes therein to adapt the same to other articles or to meet other conditions, within the scope of the following claims, without departing from the spirit of the invention.

Having fully described my invention, what I claim as new, and desire to secure 105 by Letters Patent, is:—

1. A display rack, comprising a support, front and rear uprights thereon, the latter of which is higher than the former, a brace across the tops of said rear uprights, and 110

a frame pivoted to the tops of said front uprights and adapted to bear against said rear uprights to bind displayed articles therebetween.

5 2. A display rack, comprising front and rear uprights, the latter of which are higher than the former, a frame, pivots passed through the sides thereof, below the center thereof, and through the tops of said front uprights, whereby said frame will bear

against said rear uprights through gravity to bind displayed articles therebetween.

In testimony whereof I have signed my name to this specification in the presence of the subscribing witnesses.

ORVILLE F. KIME.
